UNITED STATES PATENT OFFICE.

HENRY Y. EAGLE, OF BROOKLYN, NEW YORK.

ELECTROLYTIC APPARATUS.

Application filed November 12, 1920. Serial No. 423,512.

To all whom it may concern:

Be it known that I, HENRY Y. EAGLE, a citizen of the United States, residing in the borough of Brooklyn, county of Kings, and

5 State of New York, have invented certain new and useful Improvements in Electrolytic Apparatus, of which the following is a specification.

In present electrolytic tank practice, say 10 in the manufacture of electrolytic copper, there is a limit to the size of the main electrical conductor going into and out of the tank and this has limited the size of the tank to the dimensions corresponding to the number 15 of electrodes which, at the allowable current capacity of the single conductor, would give a practical current density.

I have found that very considerable and unexpected advantages can be secured by 20 leading the current through a plurality of main conductors into a single tank, each of which conductors may have the size practicable for the single mains heretofore used. By the use of a plurality of mains I multiply correspondingly the amount of electrical energy which can be put into a single tank, and thus increase the size of the single tank in similar proportion. This has advantages from the standpoint of construction 25 as well as from the standpoint of operation, as recited more fully hereinafter.

The accompanying drawings illustrate an embodiment of the invention.

Fig. 1 is a plan of a tank;

35 Fig. 2 is partly a side elevation and partly a central longitudinal vertical section thereof;

Fig. 3 is an elevation of the right hand end in Fig. 1;

40 Fig. 4 is a transverse section on a line 4—4, Figs. 1 and 2, showing one of the anodes;

Fig. 5 is a section on the line 5—5, Figs. 1 and 2, showing one of the cathodes;

45 Figs. 6 and 7 are diagrammatic views in plan and in end view, respectively of an arrangement of conductors and tanks.

The tanks may be constructed of various materials. I prefer reinforced concrete lined 50 where necessary with mastic asphalt, sheet lead or any suitable solution-resistant material and have shown the bottom 1, side walls 2 and end walls 3 and 4 of this material. The solution enters at the inlet end 3 through a lead pipe 5 which passes up over the end of the tank and flows continuously

through the tank from the inlet end to and over the outlet end wall 4 into a concrete box 6 whence it is drawn off through a lead pipe 7.

I have indicated at 8 and 9 in dotted lines baffles which may be interposed to direct the flow of the solution from one section of the tank to another and to break up stratification. It will be understood that these 65 baffles may be arranged at a number of points, only one location therefor being illustrated. The supply of solution is brought to the tanks in a main 10 of stoneware which may be provided with a branch 11 extending 70 alongside the tank and having fittings 12 at intervals to which smaller pipes may be connected and led up over the side wall into the tank to secure individual circulation for each of the sections of the tank in cases 75 where such individual circulation may be found advisable.

The current is brought to the apparatus from a main 13 connected to the end of a conductor bar 14 which, as shown in Fig. 4, 80 rests on a wooden insulating strip 15 on a wall 2 of the tank. Resting on this conductor 14 and in contact therewith are the corresponding ends of cross-bars 16 which carry the anodes 17; the opposite ends of the several bars 16 resting on an insulating strip 18 on a conductor-bar 19 which rests on an insulating strip of wood 20 on the opposite wall 2 of the tank. Each of the cathodes 21 for the section of the tank under consideration has its supporting cross-bar 22 with one 85 end resting on an insulating block 23 on the conductor-bar 14 and has its opposite end resting on and in contact with the conductor-bar 19 on the opposite wall 2 of the 90 tank. The current therefor passes from the conductor-bar 14 through the anodes and the solution and the cathodes to the opposite conductor-bar 19. The conductor-bar 14 supplies current to a group 24 of electrodes; there being a number of similar groups indicated at 25, 26, 27 and 28. The conductor-bar 14 extends over the length of the first group 24 only. The conductor-bar 19 extends along the opposite wall and over 100 the groups 24 and 25 of the electrodes so as to convey the current from the cathodes of the latter to the anodes of the second group, the cathodes of which are in contact with a third conductor-bar 29 which is connected 105 to the cathodes of the group 25 and with the anodes of the group 26. The cathodes of

60

90

95

100

105

110

the latter group in turn extend therefrom to make connection with the anodes of group 27; the cathodes of the latter making contact with a conductor-bar 31 which conveys the current to the anodes of the last group 28. Opposite the conductor-bar 31 for the last group of electrodes is a conductor-bar 32 and the end of the latter is connected to a bar or electric cable 33 which goes to the return wire of the electric system. In each group of electrodes as between the bars 14 and 19 or the bars 19 and 29 respectively the number of electrodes in the group is limited by the current capacity of the conductor bars 14 and 19, etc., and is preferably the maximum number of electrodes which can be used to get the desired current density.

The bar 33 will go directly to the return wire where a single tank is in question. But most plants will include a number of separate tanks, in which case the bar 33 from the end of the first tank will be the leading-in bar to the next tank. This is illustrated in Figs. 6 and 7 where the bar 33 connects directly to a bar 34 of the next tank; through which the current passes in succession by way of bars 35, 36, 37, 38 and 39 and thence to a leading-out-bar 40 which goes to the next tank; and so on through the series until we come to the leading-out-bar 41 of the last tank which constitutes or connects with the return wire 42 of the electrical supply system. The successive tanks in Fig. 7 are numbered 43, 44, 45 and 46.

Each tank is made with its bottom sloping toward the outlet end and with a box or sump 47 at the lower end with an opening therein closed by a plug valve 48 which may be removed when the slimes are to be withdrawn. A single launder 49 may be arranged as in Fig. 2 and extended across under the lower end of all the tanks in use, to carry off the slimes therefrom.

The above described arrangement permits of a considerable increase in the size of the tanks compared with that which has been previously used. It also makes possible the building of all the tanks in the room at the same elevation. Where a number of separate tanks have been used in a cascade arrangement, with the overflow from one falling into the inlet end of the other there has been a considerable expense in the building of the ends of the tanks with their expensive linings and solution spouts, which expense is largely eliminated by the present invention. The circulation in the tank of my invention is much simplified as compared with the old system, and the splash between the individual small tanks which corrodes the tank ends and bio-rods is eliminated. The conductor-bar system is also cheapened in the elimination of the bonds which have previously been required to take care of the drop from tank to tank. The

floor construction is simplified and cheapened by building all the tanks on the same level.

The accumulation of slime is very easily taken care of. It can be sluiced from all of a set of tanks to a single launder as shown 79 and which requires comparatively little head-room.

There is also a considerable advantage in the operation of all these groups of electrodes in a single tank instead of in separate tanks for the separate groups. When the solution is electrolyzed by the use of insoluble anodes an amount of chemical work is performed in the tank in direct proportion to the amount of electrical energy put into the tank. In many processes this chemical work results in regeneration of acid in the tank. If the diffusion of the solution is such a tank is comparatively free or unimpeded the composition of the solution 35 tends to maintain itself throughout the whole tank at approximately the composition of the outflowing end. For this reason the acid content of the solution in the arrangement herein described will be higher 36 than the average acid content of a series of smaller tanks. The conductivity of the electrolytic solution is greatly dependent on its acid content. It is evident, therefore, that the power consumption in the herein described tank will be appreciably less than the total power consumption in the series of smaller electrolytic tanks which it replaces. The baffles 8, 9 may be used to cut down current leakage from one group of electrodes 100 to the next, and may also be arranged to direct the flow of solution in the tanks in such a way as to prevent stratification. Either fixed or removable baffles may be used and they may be variously designed. The 105 hydrostatic pressure on opposite sides thereof will be substantially the same so that no great strength is required for them. Also they should be arranged to interfere as little 110 as possible with the rate of diffusion of the 115 solution throughout the tank.

The arrangement of the conductor-bars in series as illustrated permits of an increase of the size of the tank to any desired extent, each group of electrodes being 115 served by a conductor which is in series with the next group. However, each group of electrodes might be served by a single conductor in parallel with the other conductors in the same circuit. Or each group might 120 be served by a conductor on a different electrical circuit. Or various combinations of these circuit arrangements might be used.

Instead of building each tank with its own separate side walls the tanks might be 125 arranged in pairs or other groupings with a common wall between each two tanks and with common conductors.

Though I have described with great particularity of detail certain specific embodiment

ments of my invention yet it is not to be understood therefrom that the invention is restricted to the particular embodiments disclosed. Various modifications in detail and

5 in the arrangement of the parts may be made by those skilled in the art without departing from the invention as defined in the following claims.

What I claim is—

- 10 1. An electrolytic apparatus comprising a single tank through which the electrolyte can flow continuously and a plurality of groups of electrodes in said tank, each group comprising anodes and cathodes, and the
- 15 anodes of one group receiving current from a different conductor from that which supplies current to another group.
- 20 2. An electrolytic apparatus comprising a single tank through which the electrolyte can flow continuously and a plurality of groups of electrodes in said tank, each

group comprising anodes and cathodes, the cathodes of each group being connected to a conductor which conveys current to the anodes of the next group.

25

3. An electrolytic apparatus comprising a single tank for the electrolyte and a plurality of groups of electrodes each group receiving current from a different conductor and baffles between the sections of the tank 30 served by the different groups.

4. An electrolytic apparatus comprising a single tank for the electrolyte and a plurality of groups of electrodes each group receiving current from a different conductor 35 and means for circulating the electrolyte separately through the sections of the tank served by the different groups of electrodes.

In witness whereof, I have hereunto 40 signed my name.

HENRY Y. EAGLE.
